UNITED STATES PATENT OFFICE.

CHARLES F. McBEE, OF ATHENS, OHIO.

LOCK FOR LOOSE-LEAF BINDERS.

1,182,497.

Specification of Letters Patent.

Patented May 9, 1916.

Application filed October 21, 1912. Serial No. 726,912.

To all whom it may concern:

Be it known that I, CHARLES F. McBEE, a citizen of the United States, residing in Athens, county of Athens, and State of Ohio, have invented a new and useful Improvement in Locks for Loose-Leaf Binders, of which the following is a specification.

The object of my invention is to facilitate the filing of loose leaves in a temporary binder and to so construct the locks thereon as to preserve the posts on which the leaves are secured.

My object is further to provide simple, durable, locks which will be strong and of little expense to construct.

A further object is to divide the pressure which will be placed on the posts and distribute it evenly on opposite sides thereof.

I am aware many locks for this purpose have been designed and patented, but in all of the same the continual securing and removing of them from the receiving posts soon loosens and weakens the post and it is now my purpose to produce a lock which instead of causing weakness in the post will strengthen the same.

My invention consists of certain details of construction hereinafter set forth, pointed out in my claims, and illustrated in the accompanying drawing, in which—

Figure I shows a plan view of my locks secured to a removable cover which is in place in a temporary binder; Fig. II shows a sectional view of a binder provided with a removable cover on which my improved locks are secured; Fig. III shows a side elevation view of the same the temporary cover being reversed and joined to the posts, and Figs. IV and V show detail views of my lock.

My invention is limited to the lock feature in that class of loose leaf binder in which a temporary cover, designed to lock over protruding posts, is used to hold the sheets on the posts, the temporary cover being removable and by reversing and joining standards to the posts the sheets may be turned over.

Referring to the accompanying drawings the reference numeral 10 is used to indicate the double back of a loose leaf binder, the lower section of which is provided with a hinged flap in which are secured two similar hollow posts 11 and 12, designed to project upwardly when the hinged flap is doubled back, and resting on the said section, and the upper section is provided with a

like hinged flap in which are orifices to receive the posts when the sections of the temporary binder are secured together to form a book. The numeral 13 indicates the temporary cover I employ. On the upper surface of the temporary cover and near the outer edge thereof, I have mounted two arcuate transfer members 13' and 14' each of said members having contracted tongues which are pivotally held in slotted swivel lugs 15' and 16', respectively, said swivel lugs being mounted in receiving members 17' and 18', respectively. These transfer members have their outer ends shaped to be received by the hollow posts and are designed to be so received to constitute means, when desired, to transfer papers held by the posts. The operation thereof is obvious. The temporary cover is provided with orifices, in line with the posts 11 and 12, respectively, and on the upper surface of the temporary cover, and over their respective orifices I secure my locks. Each lock is comprised of three main parts, a base, a leaf spring, and a pivotally mounted lever clasp. The base 14 preferably metal, is secured by rivets, or their equivalents, to the temporary cover 13, an orifice in said base being in line with the orifice in the temporary cover. The leaf spring 15 is secured near one end of the base and extends therefrom nearly the full distance of the base, and is provided with an oblong shaped orifice, of even width with the orifice in the base, the rear of said oblong orifice being slightly in advance of the rear of the orifice in the base, when the spring is not raised and held on a tension. On the forward under surface of the spring is a lug 16.

The clasp 17 is pivotally secured, by any ordinary means, near the end of the base opposite to the fastening for the spring 15, and extends forwardly under the said spring its outer edge surface, being in line with, or protruding slightly beyond the edge of the orifice in the base. On each side of the clasp are protruding lugs 18 and 19 respectively between which the spring 15 is held when the spring is in any position and the lug 19 curves inwardly and upwardly over the spring and thus forms a handle by means of which the clasp is raised and lowered.

In practical operation the clasp is raised, as shown in one position in Fig. II the spring being forced upward. The construction of the parts is such that they will re-

main in this position until the clasp is forced downward. The temporary cover is then placed on the posts which pass through the orifices in the cover base and spring. The 5 clasp is then forced downward and the leaf spring forces it until the orifice in the spring and the forward edge surface of the clasp both firmly grip the post, one on each side thereof. To remove the temporary cover the 10 clasp is elevated again and, obviously, by its construction, elevates the spring thus relieving the tension on the post.

It is obvious that, from the construction hereinbefore described, I have evenly divided 15 all the pressure on the post to two opposite sides thus insuring strength and durability rather than to tend to weaken the post.

Having thus described my invention what 20 I claim and desire to secure by Letters Patent of the United States is:

1. In a temporary binder a lock comprising in combination a base, with an orifice therein, adapted to be secured to the temporary 25 cover; a leaf spring, with an oblong orifice therein, secured to the base; a lever pivotally secured to the base and engaging

the under surface of the spring, the outer end of said lever being in advance of the edge of the orifice in the base when the 30 lever is in its lowermost position, all arranged and combined substantially as shown and described.

2. In a temporary binder a lock comprising in combination a base, with an orifice therein, adapted to be secured to the temporary cover; a leaf spring, with an oblong orifice therein which is slightly in advance of the orifice in the base, secured to one end of the base; a lug 35 on the under surface at the outer end of the spring; a lever pivotally secured to the end of the base opposite the secured end of the spring, and extending underneath the spring, its outer end being in advance of the edge of the orifice in the base when the lever is in its lowermost position; lugs on said lever 40 designed as a handle thereto, all arranged and combined substantially as shown and described.

CHARLES F. McBEE.
